UNITED STATES PATENT OFFICE

MARC BIRKIGT, OF BOIS-COLOMBES, FRANCE

CRANK-SHAFT CASING

Application filed June 10, 1929, Serial No. 369,745, and in Belgium March 14, 1929.

The present invention relates to crank-shaft casings and, more particularly, to those of the type commonly employed in internal combustion engines.

One of the objects of the invention is to provide a crank shaft casing designed to permit cooling of the motor and crank-shaft bearings by circulation of a cooling fluid.

Other objects will appear in the course of the detailed description now to be given with reference to the accompanying drawings in which:—

Fig. 1 is a transverse section (line 1—1 of Fig. 3) through a casing constructed in accordance with the invention;

Fig. 2 is a section taken on line 2—2 of Fig. 1;

Fig. 3 is a section on line 3—3 of Fig. 1;

Figs. 4 and 5 are sections taken on lines 4—4 and 5—5, respectively, of Fig. 1.

Referring to the various figures of the drawings, there is shown a casing assembly adapted to be used on a multicylinder or V-type motor consisting of a pair of castings *a*, *a'* forming the upper and lower halves of the casing and including the corresponding halves *b* of a plurality to bearings for a crank-shaft (not shown) supported by intermediate walls *c* and in the extremities of the casing assembly, said walls *c* having hollow chambers *d* formed therein permitting the circulation of air,—a pair of passages *e*, *f*, connected tangentially to the interior of chambers *d* and assuring circulation of air

via inlets and outlets *g*, *g* turned either towards or away from the front of the vehicle (or as shown with one turned towards the other away),—a passage *h* permitting circulation of air between upper and lower chambers *d* of each half of the crank-case,—bolts *i* traversing the bottom of the lower casing *a* and screwing into upper element *a'*,—a lubricating conduit *j* traversing lower chamber *d*,—and a lubricant feed conduit *k*.

From the foregoing it will be seen that when the motor is mounted on a vehicle, air will enter by way of one orifice *g*, circulate around bearings *b*, and lubricating conduit *j*, inside chambers *d* of the casing via passages *e*, *f* and *h*, and discharge through the second

opening *g*. In the event that the motor is stationary, a pump or any other ventilating device (not shown) may be attached to one orifice *g* to assure air circulation. It is to be understood, of course, that if the stationary engine is equipped with a ventilating fan assuring movement of the air past the casing, orifices *g* will function to effect circulation inside chambers *d* in the same manner as when the motor is mounted on an aeroplane or vehicle. Nor need air inlets *g*, *g* be both mounted in the casing bottom. One may be so mounted and the other in the top casing so as to obtain a draft.

The term "supporting element" as used in the claims is intended to cover the whole portion shown in Fig. 3, that is, the wall *c*, the chamber *d*, the bearing support *b*, and the portion of the wall which supports the conduit *j*. That is, the shells *a* and *a'* form the outer walls of the casing while the cross walls supported by these shells form the supporting element.

Motors fitted with crank-cases of the type described are sufficiently well cooled to permit substantial reductions in bearing dimensions and considerable saving in lubricant consumption.

Obviously, the invention is not limited to the use of air as a cooling fluid. Water, oil or any other desired fluid may be circulated through chambers *d* by any appropriate pumping system.

What I claim is:—

1. In a crank shaft casing, a shaft housing including a pair of shells adapted to house a rotating shaft, a bearing positioned inside said shells and in spaced relation to the walls thereof, a supporting element extending between said bearing and said shells, said supporting element having a passage formed therethrough in proximity to said bearing and communicating with the atmosphere, whereby air may circulate through said passage and through the spaces between said bearing and said shells to cool said bearing.

2. A structure as defined in claim 1 in combination with a lubricating conduit positioned inside said supporting element and communicating with said bearing.

3. In a crank-case, a pair of shells each forming a portion of a bearing, each of said shells being shaped to provide a chamber external to the bearing portion, each of said shells being also provided with passages permitting the flow of air from the chamber of one shell to the chamber of the other, said chamber communicating with the atmosphere, said chambers enclosing substantially the whole periphery of the bearing, and bolts extending between said shells, said bolts traversing said shells in proximity to said bearing and within the geometrical limits of said chambers in a plane transverse to the axis of the bearing.
4. A crank shaft casing comprising a pair of shells, a plurality of aligned intermediate wall sections in each of said shells, each of said wall sections carrying a portion of a bearing for the crank shaft, said wall sections having shell portions around the bearing portions to provide chambers external to the bearing portions, said shell portions being provided with passages permitting the flow of air from the chamber of one shell to the chamber of the other, said chambers and bearing portions enclosing substantially the whole periphery of the crank shaft.

In testimony whereof I have signed this
specification.

MARC BIRKIGT.
